[57] CLAIM

The ornamental design for a soap dispenser or the like,
as shown and described.

DESCRIPTION

FIG. 1 is a top, front, and leftside perspective view of a
soap dispenser showing my new design;

FIG. 2 is a top plan view thereof;

FIG. 3 is a bottom plan view thereof;

FIG. 4 is a front elevational view thereof;

FIG. 5 is a right side elevational view thereof, the left
side being a mirror image of that shown; and

FIG. 6 is a rear elevational view thereof.
